UNITED STATES PATENT OFFICE.

JAMES DOIG, OF BROOKLYN, NEW YORK, ASSIGNOR TO EMMA DOIG, OF BROOKLYN, NEW YORK, EXECUTRIX OF WILLIAM S. DOIG, DECEASED.

STAPLE-DRIVING MACHINE.

1,271,548.

Specification of Letters Patent. Patented July 9, 1918.

Application filed May 18, 1916. Serial No. 98,278.

To all whom it may concern:

Be it known that I, JAMES DOIG, a citizen of the United States, residing in the borough of Brooklyn, Kings county, State of New York, have invented certain new and useful Improvements in Staple-Driving Machines, of which the following is a specification.

My invention relates to a machine for driving staples through a wall or cover forming part of a box or other receptacle. I will describe a staple driving machine embodying my invention and then point out the novel features in the claim.

In the accompanying drawings, Figure 1 is a side elevation of a staple driving machine embodying my invention. Fig. 2 is a detail sectional view of a portion of the machine shown in Fig. 1, drawn to a larger scale, to show the initial position of the driving plunger relatively to a staple. Fig. 3 is also a detail sectional view, showing the position of the plunger part way of its stroke in driving a staple. Fig. 4 is a sectional view taken on the line 4—4, Fig. 2. Fig. 5 is a sectional view taken on the line 5—5, Fig. 3. Fig. 6 is a detail sectional view taken on the line 6—6 of Fig. 5. Fig. 7 is a detail view of a latching mechanism for insuring that the driving lever shall make a full stroke to drive a staple after leaving its initial driving position. Fig. 8 is a view similar to Fig. 7, but showing the latching mechanism in a different position. Fig. 9 is a detail side elevation of the latching mechanism shown in Figs. 1, 7 and 8. Fig. 10 is a detail view of a part of the machine shown in Fig. 1.

Similar letters of reference designate corresponding parts in all of the figures.

Referring to the drawings. A designates the body of the machine, which is suitably formed to carry the main operating parts of the machine, such as a driving punch C, an operating lever D connected with the driving punch, and a staple magazine E, all of which parts will be more fully described hereinafter.

The body A is provided with a suitable base a having a downwardly extending flange or lip a' by means of which the machine may be fixed in position to drive a staple or other fastening device through two walls b, b' of a receptacle B. In order to adapt the machine to driving a staple or other fastening through a reinforcing angle

b² for a corner of the receptacle B, the base a is provided with a recessed portion a² to accommodate such an angle b², and to further provide for a proper positioning of the machine at that point, a guide a³ (Fig. 10) is adjustably connected, by means of slots a⁴ and screws a⁵, with the flange a'. A flange or lip a⁶ is provided on the guide a³ for engaging an edge of the reinforcing angle b². The receptacle B shown in the drawings, is of a type in which all of the walls excepting wall b' are suitably fastened together. The wall b' serves as a cover which can be slid into and out of position, it being held in position by one or more staples which, as shown, are driven through the walls b, b' and reinforcing angle b² at an angle. It will be seen that the angular staples may be readily taken out, and without damage to the receptacle, so that the cover or wall b' can be removed.

The driving plunger C works in a suitable slot or groove c provided in the body A, which, as here shown, is angularly arranged relatively to the base a. The plunger C is held in the slot c in what may be termed its driving position, by means of a coiled spring c' which is held between a head c² carried by the plunger C and the body A. The plunger C is moved in the slot c to drive a staple or other fastener by an operating lever D, which is here shown as being pivoted or fulcrumed at d on the body A and having a suitable operating connection with the plunger C. As here shown, the lever D is forked and the two arms of the fork are pivoted or fulcrumed to the body A at d, and the connection between the lever D and the plunger C is here shown as comprising projections c³ carried by the plunger C extending into elongated openings d' in the arms of the lever D.

The magazine E for the staples X or other fastening devices is arranged so that successive staples may be fed into the path of the plunger C in the slot c. The feed of the staples as here shown is by gravity, along a plate e' which serves to successively feed the staples one at a time in the path of the driving plunger C. The plate e' is mounted in the magazine to have longitudinal movement therein, and this is accomplished, as here shown, by means of pins or projections e² carried by the magazine E which projects into slots e³ formed in the plate e'. A

spring e^4 is provided to normally hold the plate e' into the path of the plunger C. The plate e' is provided with a bevel e^5 on which the staple X to be driven rests. As the plunger C moves to drive such staple, the plate e' is moved out of the way against the action of the spring e^4 , and when the plunger C is returned to its initial position, the plate e is again returned to its initial position, and with a staple in position to be driven. This action is clearly shown in Figs. 2 and 3.

In order to insure that the plunger C shall make a complete driving stroke, I provide a latching mechanism which is shown in Figs. 1, 7, 8 and 9. As was shown, this comprises a lever F which is pivotally mounted on the body A, and provided with a latching end f and with a disengaging end f' . Pivotally mounted on the lever F is a pawl f^2 one end of which engages a stud f^3 to limit its movement in one direction. As will be seen from Figs. 7 and 8, as the driving lever D is moved to operate the plunger C, it will first engage the pawl f^2 and the lever F will thus be caused to assume the position shown in Fig. 8. As the driving lever D is moved to complete the movement

of the plunger C, it engages the end f' to move the lever F back to its initial position shown in Fig. 7. It will be seen from Fig. 8 that any attempt to return the driving lever D to its initial position before completion of the stroke is stopped by the latching end f' of the lever F.

What I claim as my invention and desire to secure by Letters Patent, is:

In a machine for driving fasteners, in combination, a body; a plunger in said body; a spring for holding the plunger in its upper or driving position; an operating member for moving the plunger to drive a fastener; a lever pivoted on the body and having a latching end and a disengaging end; a pawl pivoted on the lever and arranged to be engaged by said member to move the latching end of the lever into latching position; and means for supplying fasteners.

In witness whereof, I have signed my name to this specification, in the presence of two subscribed witnesses.

JAMES DOIG.
